UNITED STATES PATENT OFFICE

ROBERT A. NEWE, OF HOUSTON, TEXAS

ELECTROMECHANICAL ANNUNCIATOR

Application filed June 10, 1927. Serial No. 197,850.

This invention relates to new and useful improvements in an electro-mechanical annunciator.

One object of the invention is to provide a signal device specially designed for electrically transmitting signals and including means through which the device may be manually set, or restored to inactive, or non-signaling position.

Another object of the invention is to provide a signal device of the character described which, while capable of general use, is particularly adapted for use on elevators in buildings.

A further feature of the invention is to provide a signal device of the character described which is of very simple construction, may be cheaply produced and easily operated and kept in repair.

With the above and other objects in view this invention has particular relation to certain novel features of construction, operation and arrangement of parts, an example of which is given in this specification and illustrated in the accompanying drawings, wherein:—

Figure 1 shows an elevational view of the operating mechanism of the device shown partly in section.

Figure 2 shows a fragmentary sectional view taken on the line 2—2 of Figure 1.

Figure 3 shows a cross sectional view thereof, taken on the line 3—3 of Figure 1, and

Figure 4 shows a fragmentary cross sectional view taken on the line 4—4 of Figure 1.

Referring now more particularly to the drawings, wherein like numerals of reference designate similar parts in each of the figures, the numeral 1 designates the enclosing casing and in the casing are the pairs of electro-magnets, one magnet of each pair being designated by the numeral 2 and the other magnet of each pair being designated by the numeral 3. Associated with the magnets are the pairs of lights, the lights of each pair being designated by the numerals 4 and 5, respectively. When the apparatus is used in an elevator the lights 4 may in-

dicate a movement of the elevator in one direction and the lights 5 will then indicate its movement in the other direction.

Associated with the respective pairs of magnets 2, 3 are the corresponding pairs of switch arms 6, 7, whose inner ends are pivotally connected to the respective anchors 8 which are secured to the casing 1 and are preferably located between the corresponding magnets. The magnets are wired in the respective electrical circuits 9, 10, which may be completed or broken through the conventional push button switches 11, 12 located in the hallways of the respective floors of the building, preferably adjacent the elevator shaft, or at any other desired place, depending on the character of use of the signal device.

The magnets 2, 3, are wired in the electrical circuits 13, 14, respectively. Incorporated into each light circuit are the switch tongues 15, 16, which are anchored to the casing 1 and spaced apart. The upper end of each tongue 15 is formed into an arm clamp 17, adapted to engage and hold the corresponding switch arm 6 or 7 as the case may be, in inactive, or open position.

Release rods 18, 19, are provided whose ends are formed with the aligned eccentric wrists 20, 21, and 22, 23, respectively, which are mounted to rotate in the spaced end bearings 24, 25, and 26, 27, respectively. The wrists 21, 23 have the arms 28, 29 respectively fixed and extending at right angles thereto and which rest on the yieldable seats 30, 31.

Push rods, as 32, are slidably mounted in suitable bearings in the casing 1 and have their lower ends working against the corresponding arms 28, 29. The release rods 18, 19, work underneath the switch arms 6 and 7 respectively.

In operation when it is desired to give a signal the corresponding switch 11, or 12 may be closed which will be effective to complete an electrical circuit through the corresponding electro-magnet 2 or 3 as the case may be and the magnet being energized will release the corresponding switch arm 6 or 7 from its clamp 17, and will carry said

arm into position between the tongues 15, 16, thus completing a circuit through the corresponding light circuit 13 or 14 and the light connected into said circuit will be illuminated.

5 In order to extinguish the light, the corresponding push rod 32 may be depressed which in turn will depress the corresponding arm 28, or 29, and elevate the corresponding release rod 18, or 19, which will carry the corresponding switch arm 6 or 7 out of contact with the tongue 16 and into the clamp 17 by which it will be held until its corresponding magnet is again energized.

10 15 Any number, or all, of the lights 2 and 3 may be illuminated either simultaneously, or successively and they may be simultaneously extinguished by depressing the push rods 32.

15 20 When the rods 32 are released the springs 30, 31 will operate to return the release rods 18, 19 to their original or inactive position.

25 I have shown and described which I now consider the preferred form of the apparatus, this showing, however, constituting only an illustration of the principle of the invention. It is evident that mechanical changes may be made and equivalents substituted for the parts shown and I hereby reserve the right to make such structural changes or modifications as may be found desirable and as may be comprehended within the scope of the appended claims.

30 35 What I claim is:—

35 40 1. In a signal device, a switch arm, pivotally mounted at one end, a pair of spaced switch tongues between which the switch arm works, the free end of one tongue being overturned and formed into a clamp adapted to engage and hold the switch arm, a release rod arranged to actuate said arm into engaged relation with said clamp.

45 50 2. In a signal device a switch comprising a pair of spaced parallel switch tongues, a switch arm, said arm being pivotally mounted at one end and adapted to work between the corresponding tongues of said pair, means operable against said arm to carry said arm out of contact with one tongue of said pair the free end of the other tongue having an arcuate, flexible grip forming means to engage and hold the switch arm out of said contact.

55 55 In testimony whereof I have signed my name.

ROBERT A. NEWE.
